(57) **CLAIM**

The ornamental design for a display mount with dual articulating arms, as shown and described.

DESCRIPTION

FIG. 1 is a front perspective view of a display mount with dual articulating arms according to the invention;

FIG. 2 is a front elevation view of the display mount with dual articulating arms depicted in FIG. 1;

FIG. 3 is a side elevation view of the display mount with dual articulating arms depicted in FIG. 1;

FIG. 4 is an opposing side elevation view of the display mount with dual articulating arms depicted in FIG. 1;

FIG. 5 is a top plan view of the display mount with dual articulating arms depicted in FIG. 1; and,

FIG. 6 is a bottom plan view of the display mount with dual articulating arms depicted in FIG. 1.

The rear elevation of the depicted mount is not claimed, and hence is not depicted. The portions of the display mount with dual articulating arms shown in broken lines form no part of the claimed design.
